RAILWAY CAR RETARDER

John W. Livingston, Wilkinsburg, Pa., assignor
to The Union Switch & Signal Company, Swiss-
vale, Pa., a corporation of Pennsylvania

Application July 9, 1935, Serial No. 30,528

24 Claims. (Cl. 104—26)

My invention relates to railway car retarders, and particularly to car retarders of the track brake type used in classification or hump yards of railroads for controlling the speed of cars.

5 One object of my invention is the provision of improved apparatus for automatically controlling the braking action of a car retarder of the type described in accordance with the speed of cars approaching or passing through the retarder.

I will describe two forms of car retarder controlling apparatus embodying my invention, and will then point out the novel features thereof in claims.

15 In the accompanying drawings, Fig. 1 is a diagrammatic view illustrating one form of apparatus embodying my invention. Fig. 2 is a left-hand end view of the timing unit U^a forming part of the apparatus illustrated in Fig. 1. Fig. 3 is a vertical sectional view of a portion of the timing unit U^a shown in Fig. 2. Fig. 4 is an enlarged end view of the contact mechanism D^1 forming part of the timing unit U^a shown in Figs. 2 and 3. Fig. 5 is a diagrammatic view illustrating another form of car retarder controlling apparatus embodying my invention.

Similar reference characters refer to similar parts in all five views.

Referring first to Fig. 1, the reference characters 1 and 1^a designate the track rails of a stretch of railway track over which cars normally move in the direction indicated by the arrow under such conditions that it is desirable to at times control the speed of the cars automatically. For example, the stretch of track here shown might be in a classification yard of the "hump" type through which cars move under the influence of gravity. It is obvious that in service of this kind, the speed of individual cars or strings of cars will vary through wide limits, depending, among other things, upon the speed at which they go over the hump, the temperature, the weight of the car and its contents, and the condition of the car as to whether it is a free running car or otherwise.

In order to control the speed of the cars, the stretch of track illustrated in the drawings is provided with a car retarder R which, in the form here shown, comprises two braking bars 2 and 3 extending parallel with, and located on opposite sides of, rail 1 , and two similar braking bars 2^a and 3^a extending parallel with, and located on opposite sides of, rail 1^a . The braking bars of each pair are so disposed that when they are moved toward the associated rail, they will occupy

positions in which they will engage the wheels or other parts of a passing car, and will thus retard the speed of the car.

The car retarder R is operated by a mechanism M which is controlled by a relay C and by a lever L . The construction of the mechanism M , and the manner in which this mechanism is controlled by the relay C and lever L forms no part of my present invention, and may, for example, be similar to that shown in Letters Patent 10 of the United States No. 1,958,293, granted to Herbert L. Bone and myself, on May 8, 1934. It is believed, therefore, that for purposes of my present invention, it is sufficient to state that when relay C is deenergized, the operating mechanism will move the braking bars to their braking or non-braking positions according as lever L occupies its right-hand or "on" position in which it is shown in the drawings, or its left-hand or "off" position, but that, when relay C becomes energized, if the braking bars do not already occupy their non-braking positions, the mechanism 15 M will automatically move them to their non-braking positions.

In accordance with my present invention novel and improved means are provided for controlling relay C in such manner that this relay will become energized automatically when the speed of a car which is traversing the stretch of track shown in the drawing falls below a speed which depends upon the setting of a manually operable speed control lever S . As here shown, these means comprise a series of relatively short insulated control sections 4^a , 4^b , 4^c , etc., which are formed in the rail 1 . These control sections will usually be of uniform length, and their lengths may be varied as conditions require, but the lengths of these sections will preferably be such that two wheels of a car can not occupy the same section at any one time.

The means for controlling relay C also comprise a plurality of timing units one of which is associated with each control section 4 , and each of which is designated as a whole by the reference character U with a suitable distinguishing exponent. These timing units are similar, and a description of one will therefore suffice for all. Referring particularly to the timing unit U^a shown in detail in Figs. 2 and 3, this timing unit comprises a driving electromagnet A and a holding electromagnet B . These electromagnets are similar and each comprises a magnetizable core 6 provided with a centrally located hole 7 , and with an annular recess 8 in one side, which recess is concentric with the hole 7 , and which recess 40 45 50 55 55

receives a winding 9. The two electromagnets A and B are secured, in axial spaced relation, to a fixed support not shown in the drawings in such manner that the sides in which the recesses 8 are formed face each other, and extending with considerable clearance through the holes in these electromagnets is a driveshaft 11. This driveshaft cooperates with all of the timing units U as will be apparent from an inspection of Fig. 1, and is driven at a constant speed in a clockwise direction, as viewed in Fig. 2, by an electric motor N shown diagrammatically in Fig. 1. Surrounding the driveshaft 11 between the electromagnets A and B are a driving disk 12 provided with a hub 13 which is keyed to the driveshaft 11 in a fixed position, and a magnetizable cam disk 14 provided with a hub 15 which is loosely mounted on the driveshaft 11. The hub 13 extends with some clearance through the hole 7 in the core 6 of the electromagnet A, and the hub 15 similarly extends with some clearance through the hole 7 in the core 6 of the electromagnet B. It will be seen, therefore, that the driving disk 12 is constantly rotated with the driveshaft, but that, the cam disk 14 is free to rotate independently of the driveshaft. A spiral spring 16 is secured at one end to the hub 15 of the cam disk 14, and at the other end to a support 10, and this spring constantly biases the cam disk 14 in a counter-clockwise direction, as viewed in Fig. 2, to a position in which a stop lug 17 formed on the cam disk engages a stop member 18 secured to a contact bracket 19. The spring 16 also biases the cam disk 14 to the longitudinal position on the driveshaft 11 in which this cam disk is midway between a clutch facing 20 secured to the driving disk 12 and a clutch facing 21 secured to an annular flange 22 formed on the core 6 of electromagnet B. The parts are so proportioned that when electromagnet A is energized, this electromagnet will exert a magnetic pull on the cam disk 14 which will cause the cam disk to slide longitudinally along the driveshaft to a position in which it frictionally engages the clutch facing 20 with sufficient force to cause the cam disk to rotate with the driving disk, in opposition to the bias of the spring 16, and that, when the electromagnet B is energized, this latter electromagnet will exert a magnetic pull on the cam disk which will cause it to slide longitudinally along the driveshaft 11 to a position in which it frictionally engages the clutch facing 21 with sufficient force to hold the cam disk, in opposition to the bias of the spring 16, in any position to which it had been previously rotated by engagement with the driving disk 12.

The timing mechanism U^a also comprises a plurality of contact mechanisms, one of which is provided for each control speed at which it is desired to have cars leave the retarder. As here shown, three such mechanisms are provided, one for high speed, one for medium speed, and one for slow speed, these mechanisms being designated by the reference characters D¹, D² and D³, respectively. These contact mechanisms are mounted on the contact support 19 at spaced points around the periphery of the cam disk 14, and in the form here illustrated, each of these mechanisms comprises a flexible contact finger 25 secured at one end to an insulating terminal block 29 by means of a terminal post 30, and provided intermediate its ends with a roller 31 which cooperates with a cam lobe 14^a formed on the cam disk 14. The free end of each contact finger 25 is trifurcated, and 75 cooperates with three fixed contact members 26,

27 and 28 (see Fig. 4) in such manner that when the cam lobe 14^a on the cam disk 14 is out of engagement with the associated roller 31, the middle trifurcation will engage the contact member 26 and will thus close a back contact 25-26, 5 10 but that, when the cam lobe 14^a is engaging the roller, the two outside trifurcations will then engage the fixed contact members 27 and 28 and will thus close front contacts 25-27 and 25-28. The fixed contact members 26, 27 and 28 are secured to the contact block 29 by means of terminal posts 32, 33 and 34, respectively. The location of the contact mechanisms D¹, D² and D³ are such, and the parts are so proportioned that these mechanisms will become operated when the electromagnet A becomes energized if and only if the electromagnet A subsequently remains energized for time intervals which are equal to, or greater than, that required for a car to traverse a distance equal to the lengths of one of the control sections 4 when the car is traveling at the high, medium or low control speed, respectively, at which it is desired to have cars leave the retarder. 15 20

It is desirable to be able to readily inspect the contact mechanisms D¹, D² and D³, and for this purpose the contact bracket 19 is pivotally supported at its upper end on a hanger 35, and is secured at its lower end to the support 10 by means of screws 36 in such manner that by releasing the screws 36 the entire contact assembly may be rotated away from the remainder of the timing unit. 30

The manually operable speed control lever S will usually be located adjacent the lever L in a position where it may be conveniently operated by the same operator who operates the lever L. As here shown, the lever S is provided with a high speed position s¹ in which it is shown in the drawings, a medium speed position indicated by a dotted line in the drawings and designated by the reference character s², and a low speed 40 position also indicated by a dotted line in the drawings and designated by the reference character s³. Operatively connected with the lever S are a plurality of contact arms one of which is provided for each control section, and each of which is designated by the reference character 5 with a suitable distinguishing exponent. The contact arm 5^a cooperates with three fixed contacts 5¹, 5² and 5³ to selectively close a contact 5^a-5¹, 5^a-5², or 5^a-5³ according as lever S occupies its s¹, its s², or its s³ position. Each of the other contact arms 5 similarly cooperates with three fixed contacts 5¹, 5² and 5³ to selectively close contacts in the same manner that the arm 5^a cooperates with the fixed contacts 5¹, 5² and 5³ to selectively close the contacts 5^a-5¹, 5^a-5² and 5^a-5³. 50 55

The electromagnet A of timing unit U^a is provided with a first energizing circuit which includes the winding of the electromagnet, a suitable source of current here shown as a battery E, rail 1^a, control section 4^a, contact 5^a-5¹ of lever S, and contact 25-26 of the associated contact mechanism D¹. This circuit becomes closed when and only when lever S occupies its s¹ position and a car wheel moves onto control section 4^a, and it will be apparent that when this circuit becomes closed, electromagnet A of unit U^a will become energized and will cause the associated cam disk 14 to rotate in the manner previously described. It will also be apparent that when this circuit becomes closed, it will subsequently remain closed for a time interval which depends upon the speed of the car which caused it to become closed unless the speed of the car 70 75

is equal to, or less than, that corresponding to the s^1 position of lever S, in which event cam disk 14 will operate contact mechanism D¹, thus causing contact 25-26 to open and deenergize electromagnet A.

Electromagnet A of timing unit U^a is also provided with a second energizing circuit which is similar to the first energizing circuit described above with the exception that this circuit includes in place of contact 5^a-5¹ of lever S and contact 25-26 of the associated contact mechanism D¹, contact 5^a-5² of lever S and contact 25-26 of the associated contact mechanism D². This circuit becomes closed when and only when lever S occupies its s^2 position and a car wheel moves onto control section 4^a, and it will be apparent that when this circuit becomes closed, the electromagnet A of unit U^a will become energized and will cause cam disk 14 to rotate in the manner previously described. It will also be apparent that when this circuit becomes closed, it will subsequently remain closed for a time interval which depends on the speed of the car unless the speed of the car is equal to, or less than, that corresponding to the s^2 position of the lever S in which event the cam disk 14 will operate the contact mechanism D², thus causing contact 25-26 to open and deenergize electromagnet A.

Electromagnet A of timing unit U^a is further provided with a third energizing circuit which is similar to the first energizing circuit with the exception that this third circuit includes contact 5^a-5³ of lever S and contact 25-26 of the associated contact mechanism D³ in place of contact 5^a-5¹ of lever S and contact 25-26 of the associated contact mechanism D¹. This latter circuit becomes closed when and only when lever S occupies its s^3 position and a car wheel enters section 4^a, and it will be apparent that when this circuit becomes closed, electromagnet A will become energized and will thus cause cam disk 14 to rotate in the manner previously described. It will also be apparent that when this circuit becomes closed, it will subsequently remain closed for a time interval which depends upon the speed of the car unless the speed of the car is then equal to, or less than, that corresponding to the s^3 position of the lever in which event cam disk 14 will operate contact mechanism D³, thus causing contact 25-26 to open and deenergize electromagnet A.

The electromagnet B of timing unit U^a is provided with a first energizing circuit which includes the winding of the electromagnet, battery E, rail 1^a, control section 4^a, contact 5^a-5¹ of lever S, and contact 25-28 of the associated contact mechanism D¹. This circuit becomes closed when and only when lever S occupies its s^1 position and the speed of a car whose wheel is traversing section 4^a is sufficiently slow to cause the contact mechanism D¹ to become operated, and it will be apparent that when this circuit becomes closed, electromagnet B will become energized. It will also be apparent that when electromagnet B becomes energized, contact mechanism D¹ will be held in its operated position in the manner previously described, with the result that after electromagnet B has once become energized under these conditions, it will subsequently remain energized until the car wheel which caused it to become energized departs from section 4^a.

Electromagnet B of timing unit U^a is also provided with a second energizing circuit which

is similar to the circuit just described with the exception that this latter circuit includes, in place of contact 5^a-5¹ of lever S and contact 25-28 of the associated contact mechanism D¹, contact 5^a-5² of lever S and contact 25-28 of the associated contact mechanism D². This circuit becomes closed when and only when lever S occupies its s^2 position and the speed of a car whose wheel is traversing section 4^a is sufficiently slow to cause the contact mechanism D² to become operated, and it will be apparent that when this circuit becomes closed, electromagnet B will become energized. It will also be apparent that when electromagnet B becomes energized, this electromagnet will subsequently remain energized and will hold the contact mechanism D² in its operated position until the car wheel, which caused the electromagnet to become energized, departs from the control section 4^a.

Electromagnet B of timing unit U^a is further provided with a third energizing circuit which is similar to the first energizing circuit with the exception that this circuit includes, in place of contact 5^a-5¹ of lever S and contact 25-28 of the associated contact mechanism D¹, contact 5^a-5³ of lever S and contact 25-28 of the associated contact mechanism D³. This circuit becomes closed when and only when lever S occupies its s^3 position and the speed of a car whose wheel is traversing section 4^a is sufficiently slow to cause the contact mechanism D³ to become operated, and it will be apparent that when this circuit becomes closed, electromagnet B will become energized. It will also be apparent that when this circuit becomes closed, it will subsequently remain closed until the car wheel which caused it to become closed departs from section 4^a.

The electromagnets A and B of each of the remaining timing units are each provided with circuits which are similar to those just described for the electromagnets A and B of timing unit U^a. Since these circuits are similar to those previously described, it is believed that they will be obvious from an inspection of the drawings without further description.

The control relay C is provided with a first series of control circuits, which circuits are rendered effective for controlling relay C when and only when lever S occupies its s^1 position, and each of which includes the contact 25-27 of the contact mechanism D¹ of a different one of the timing units U. These control circuits are similar and a description of one will therefore suffice for all. Referring particularly to the control circuit which includes the contact 25-27 of the contact mechanism D¹ of unit U^a, this circuit includes battery E, rail 1^a, control section 4^a, contact 5^a-5¹ of lever S, contact 25-27 of contact mechanism D¹, wires 40 and 41, winding of relay C and wire 42. It will be apparent, therefore, that when lever S occupies its s^1 position and a car wheel traverses any one of the control sections 4 at a speed which is sufficiently slow to cause the associated contact mechanism D¹ to become operated, the resultant closing of the contact 25-27 of such contact mechanism will complete the control circuit for relay C including this contact, and relay C will therefore become energized.

The control relay C is also provided with a second series of control circuits which are rendered effective for controlling this relay when and only when lever S occupies its s^2 position, and each of which includes the contact 25-27 of the contact mechanism D² of a different one of

the timing units U. Referring particularly to the control circuit for relay C which includes the contact 25-27 of the contact mechanism D² of unit U^a, this circuit also includes a battery E, rail 1^a, control section 4^a, contact 5^a-5² of lever S, wires 43, 45 and 41, winding of relay C and wire 42. Each of the remaining control circuits of the series is similar to that just described and will be obvious from an inspection of the drawings. It will be apparent, therefore, that when lever S occupies its s² position and a car wheel traverses any one of the control sections 4 at a speed which is sufficiently slow to cause the associated contact mechanism D² to become operated, the resultant closing of the contact 25-27 of such control mechanism will complete the circuit for relay C including this contact and relay C will therefore become energized.

The control relay C is further provided with a third series of control circuits which are rendered effective for controlling this relay when and only when lever S occupies its s³ position, and each of which includes the contact 25-27 of the contact mechanism D³ of a different one of the timing units U. Referring particularly to the control circuit for relay C which includes contact 25-27 of the contact mechanism D³ of the unit U^a, this circuit also includes battery E, rail 1^a, control section 4^a, contact 5^a-5³ of lever S, wires 44, 45 and 41, the winding of relay C and wire 42. Each of the other control circuits of the series is similar to that just described and will be obvious from an inspection of the drawings. It will be apparent, therefore, that when lever S occupies its s³ position and a car wheel traverses any one of the control sections 4 at a speed which is sufficiently slow to cause the associated contact mechanism D³ to become operated, the resultant closing of the contact 25-27 of such contact mechanism will complete the control circuit for relay C including this contact and relay C will therefore become energized.

Relay C is made sufficiently slow releasing so that when a car is traversing the stretch of track shown in the drawings at a speed which is just slow enough to cause the contact mechanisms D³ of the timing units U to become successively operated, this relay will bridge the interval of time which will elapse under these conditions between the opening of the contact 25-27 of the contact mechanism D³ of one timing unit U due to a wheel of a car having departed from the associated control section 4, and the closing of the contact 25-27 of the contact mechanism D³ of the timing unit next in advance due to the same wheel of the car having moved onto the section 4 associated with this latter timing unit.

As shown in the drawings, all parts are in the positions which they normally occupy when it is desired to retard a car which is approaching the retarder from the left, to the highest speed for which the apparatus is designed. That is to say, lever S occupies its s¹ position, the electromagnets A and B of each of the timing units U are de-energized, lever L occupies its "on" position, relay C is de-energized, and the braking bars occupy their braking positions.

With the parts in the positions just described, I will assume that a car which is traveling at a higher rate of speed than that for which the speed control lever S is set enters the retarder. As the car moves through the retarder, each time a car wheel moves onto one of the control sections 4, the electromagnet A of the associated timing unit U will become energized in the man-

ner previously described, but as long as the speed of the car is above that corresponding to the s¹ position of the lever, none of the electromagnets A will remain energized long enough to cause the associated contact mechanism D¹ to become operated. Relay C will therefore remain de-energized, and the car retarder will therefore continue to slow down the car. As soon, however, as the car has been slowed down by the car retarder to a speed which is equal to, or less than, the speed corresponding to the s¹ position of lever S, and a wheel of the car traverses any one of the control sections 4, the contact mechanism D¹ of the associated timing unit U will then become operated and will close its contact 25-27, thus completing one of the previously described control circuits for relay C. Relay C will therefore become energized, and when this relay becomes energized, the braking bars will be moved to their non-braking positions by the operating mechanism M in the manner previously described. After the braking bars have once been moved to their non-braking positions, no further retardation of the car will take place unless the car again speeds up to a speed which is above that corresponding to the s¹ position of lever S while the car is still within the limits of the retarder. Assuming that the car does this, then as soon thereafter as the contact mechanism D¹ which last became operated is restored to its normal position and an interval of time equal to the release time of relay C has elapsed thereafter, relay C will become de-energized and will subsequently remain de-energized because, under these conditions, none of the other contact mechanisms D¹ will subsequently become operated. As soon as relay C becomes de-energized, the braking bars of the car retarder R will, of course, again move to their braking positions and will start to again slow down the car. It will be seen, therefore, that when lever S occupies its s¹ position and a car which is traveling at a higher control speed than that corresponding to this position of the lever enters the retarder, the car retarder will automatically retard the car in such manner as to cause it to leave the retarder at the control speed corresponding to the s¹ position of the lever.

I will now assume that the operator has moved the speed control lever S to its s² position and that a car which is traveling at a higher speed than that corresponding to this position of the lever enters the retarder. Under these conditions, the operation of the apparatus will be similar to that just described with the exception that the contact mechanisms D² of the timing units will be rendered effective for controlling relay C, with the result that the braking bars will now slow down the car as long as the car speed is above that corresponding to the s² position of the lever.

The operation of the apparatus, when lever S occupies its s³ position and a car traverses the stretch of track shown in the drawings, is similar to that described above when lever S occupied its s¹ position and a car traversed the stretch of track shown in the drawings with the exception that, under these conditions, the contact mechanisms D³ of the timing units U are rendered effective for controlling relay C, and the braking bars will therefore slow down the car as long as the speed of the car is above that corresponding to the s³ position of the lever.

Referring now to Fig. 5, in the modified form of apparatus here illustrated the timing units 75

U instead of each being provided with three contact mechanisms D¹, D², and D³ as shown in Fig. 1, are each provided with only one contact mechanism D¹, and the shaft 11 which drives the driving disks 12 of the timing units, instead of being driven at a constant speed in the manner previously described, is arranged to be driven at a plurality of different speeds by means of a variable speed motor N¹, the speed of which may be controlled by any of the well-known forms of speed control devices. As here shown, the speed of the motor N¹ is controlled by a speed controller SC comprising a speed control lever 50 which is movable to three positions s¹, s², and s³, and which controls the supply of energy to the motor N¹ in such manner that the motor will be driven at a different speed in each different position of the speed control lever. Speed controllers of the type described are well-known, and it is believed, therefore, that for purposes of my present invention a more detailed description of this speed controller is unnecessary.

With the timing units arranged in the manner just described, it will be apparent that the time interval which will elapse after the electromagnet A of a timing unit becomes energized and before the associated contact mechanism D¹ becomes operated will vary with the setting of the speed control lever 50, and the parts are so proportioned that according as lever 50 occupies its s¹, s², or s³ position, these time intervals will be equal to those required for a car to traverse a distance equal to the lengths of one of the control sections 4 when the car is traveling at a high, medium, or low control speed, respectively.

The apparatus shown in Fig. 5 further differs from that shown in Fig. 1 in that the electromagnets A and B of the timing units U of the apparatus shown in Fig. 5 are each provided with only one control circuit, thus rendering the use of the speed control lever S unnecessary. Referring particularly to the timing unit U^a, the control circuit for electromagnet A of this timing unit includes battery E, rail 1^a, control section 4^a, contact 25-26 of contact mechanism D¹, and the winding of electromagnet A; while the control circuit for electromagnet B of the timing unit U^a includes battery E, rail 1^a, control section 4^a, contact 25-28 of contact mechanism D¹, and the winding of electromagnet B. It will be seen, therefore, that each time a car wheel moves onto control section 4^a, electromagnet A of timing unit U^a will become energized and will subsequently remain energized until the car leaves the section unless the car is traveling at a speed which is sufficiently slow to cause contact mechanism D¹ to become operated, whereupon electromagnet A will become deenergized and electromagnet B will become energized. It will also be seen that when electromagnet B once becomes energized, it will remain energized and will retain contact mechanism D¹ in its operated position until the car wheel which caused it to become energized subsequently leaves control section 4^a. The control circuits for the electromagnets A and B of each of the other timing units are similar to those just described for the electromagnets A and B of the timing unit U^a, and the operation of the other units is likewise similar to the operation of the unit U^a.

Relay C is controlled by the contact mechanism D¹ of each timing unit U in exactly the same manner as in Fig. 1.

The operation of the system as a whole when

constructed as shown in Fig. 5 is similar to that of the system shown in Fig. 1 with the exception that the same contact mechanisms D¹ function for all control speeds, and that the different control speeds are obtained by moving the speed control lever 50 to different positions, thus causing the contact mechanisms to operate at the expiration of different intervals of time in the manner previously described.

It should be pointed out that while, with the apparatus constructed as illustrated in Fig. 5, I have shown means for driving the shaft 11 at only three selected speeds, this shaft might equally well be driven by other well-known means in such manner that its speed could be continuously varied through wide limits, and that with such a means for driving the shaft, the speed at which cars will leave the retarder may be continuously varied through wide limits.

One advantage of a speed control system for railway car retarders embodying my invention is that, since the driving disks 14 of all of the timing units rotate at the same speed, and since the contact mechanisms are located at the same relative positions with respect to the associated driving disk on all of the units, the timing of all of the units will be uniform.

Another advantage of a speed control system for car retarders embodying my invention is that, since the timing of the timing units depends entirely upon the rotational speed of shaft D, the timing of each of the units may be simultaneously varied in a very simple manner by simply changing the speed of the shaft 11.

A further advantage of a speed control system for car retarders embodying my invention is that, since the timing of the whole system depends entirely on the rotational speed of the shaft 11, and since this shaft is driven by a constant speed motor, the timing of the system will not vary with variations in the ambient temperature. If, however, temperature compensation is desired to compensate for increases in car resistance at lower temperatures, a variable speed motor or a gear box can be used to accomplish the desired result.

Although I have herein shown and described only two forms of car retarder controlling apparatus embodying my invention, it is understood that various changes and modifications may be made therein within the scope of the appended claims without departing from the spirit and scope of my invention.

Having thus described my invention, what I claim is:

1. In combination, a stretch of railway track, an insulated control section formed in one rail of said stretch, a member biased to one position, a contact mechanism including a normally closed and a normally open contact, means controlled by said member for operating said contact mechanism to open said normally closed contact and close said normally open contact when said member is moved away from said one position a predetermined amount, an electromagnet, means effective when said electromagnet becomes energized for moving said member away from said one position at a predetermined rate of speed, an energizing circuit for said electromagnet including said control section, the opposite rail of said stretch and said normally closed contact; and an electroresponsive device controlled by said normally open contact.

2. In combination, a stretch of railway track,

an insulated control section formed in one rail of said stretch, a member biased to one position, a contact mechanism including a normally closed and a normally open contact, means controlled

- 5 by said member for operating said contact mechanism to open said normally closed contact and close said normally open contact when said member is moved away from said one position a predetermined amount, an electromagnet, means
  - 10 effective when said electromagnet becomes energized for moving said member away from said one position at a predetermined speed, an energizing circuit for said electromagnet including said control section, the opposite rail of said
  - 15 stretch and said normally closed contact; and means controlled by said normally open contact for controlling the speed of a car traversing said stretch.

3. In combination, a stretch of railway track, an insulated control section formed in one rail of said stretch, a member biased to one position, a contact mechanism including a normally closed and a normally open contact, means controlled by said member for operating said contact mechanism to open said normally closed contact and close said normally open contact when said member is moved away from said one position a predetermined amount, an electromagnet, means effective when said electromagnet becomes energized for moving said member away from said one position at a predetermined speed, an energizing circuit for said electromagnet including said control section, the opposite rail of said stretch and said normally closed contact; a car retarder associated with said stretch for controlling the speed of a car traversing said stretch, and means for controlling said car retarder controlled by said normally open contact.

4. In combination, a stretch of railway track,
40 an insulated control section formed in one rail
of said stretch, a member biased to one position,
a contact mechanism including a normally closed
and a normally open contact, means controlled
by said member for operating said contact mech-
45 anism to open said normally closed contact and
close said normally open contact when said mem-
ber is moved away from said one position a pre-
determined amount, an electromagnet, means
effective when said electromagnet becomes ener-
50 gized for moving said member away from said
one position at a predetermined speed, an ener-
gizing circuit for said electromagnet including
said control section, the opposite rail of said
stretch and said normally closed contact; a slow
55 acting relay controlled by said normally open
contact, and means controlled by said relay for
controlling the speed of a car traversing said
stretch.

5. In combination, a stretch of railway track, an insulated control section formed in one rail of said stretch, a member biased to one position, a contact mechanism including a normally closed and a normally open contact, means controlled by said member for operating said contact mechanism to open said normally closed contact and close said normally open contact when said member is moved away from said one position a predetermined amount, an electromagnet, means effective when said electromagnet becomes energized for moving said member away from said one position at a predetermined speed, an energizing circuit for said electromagnet including said control section, the opposite rail of said stretch and said normally closed contact; a relay; a circuit for said relay including said nor-

mally open contact, said control section, and the opposite rail of said stretch; and means controlled by said relay for controlling the speed of a car traversing said stretch.

6. In combination, a stretch of railway track, 5
an insulated control section formed in one rail
of said stretch, a member biased to one position,
a contact mechanism including a normally closed
and two normally open contacts, means
controlled by said member for operating said 10
contact mechanism to open said normally closed
contact and close said normally open contacts
when said member is moved away from said one
position a predetermined amount, a first electro- 15
magnet, means effective when said first electro-
magnet becomes energized for moving said mem-
ber away from said one position at a predeter-
mined speed; an energizing circuit for said first 20
electromagnet including said control section, the
opposite rail of said stretch and said normally
closed contact, a second electromagnet, means
effective when said second electromagnet be-
comes energized for holding said member in the 25
position which it then occupies; an energizing
circuit for said second electromagnet including
said control section, the opposite rail of said
stretch and one of said normally open contacts;
and an electroresponsive device controlled by the
other normally open contact.

7. In combination, a stretch of railway track, 30
an insulated control section formed in one rail
of said stretch, a member biased to one position,
a contact mechanism including a normally closed
and two normally open contacts, means con- 35
trolled by said member for operating said con-
tact mechanism to open said normally closed
contact and close said normally open contacts
when said member is moved away from said one
position a predetermined amount, a first elec- 40
tromagnet, means effective when said first elec-
tromagnet becomes energized for moving said
member away from said one position at a pre-
determined speed; an energizing circuit for said
first electromagnet including said control section,
the opposite rail of said stretch and said normal- 45
ly closed contact, a second electromagnet, means
effective when said second electromagnet be-
comes energized for holding said member in the
position which it then occupies; an energizing
circuit for said second electromagnet including
said control section, the opposite rail of said 50
stretch and one of said normally open contacts;
and means controlled by the other normally open
contact for controlling the speed of a car trav-
ersing said stretch. 55

35
8. In combination, a stretch of railway track, an insulated control section formed in one rail of said stretch, a member biased to one position, a contact mechanism including a normally closed and two normally open contacts, means controlled by said member for operating said contact mechanism to open said normally closed contact and close said normally open contacts when said member is moved away from said one position a predetermined amount, a first electromagnet, means effective when said first electromagnet becomes energized for moving said member away from said one position at a predetermined speed; an energizing circuit for said first electromagnet including said control section, the opposite rail of said stretch and said normally closed contact; a second electromagnet, means effective when said second electromagnet becomes energized for holding said member in the position which it then occupies; an energizing circuit for said second 60 65 70 75

electromagnet including said control section, the opposite rail of said stretch and one of said normally open contacts; a car retarder associated with said stretch, and means controlled by the 5 other normally open contact for controlling said car retarder.

9. In combination, a stretch of railway track, an insulated control section formed in one rail of said stretch, a member biased to one position, a 10 contact mechanism including a normally closed and two normally open contacts, means controlled by said member for operating said contact mechanism to open said normally closed contact and close said normally open contacts when said member 15 is moved away from said one position a predetermined amount, a first electromagnet, means effective when said first electromagnet becomes energized for moving said member away from said one position at a predetermined speed; an energizing circuit for said first electromagnet including said control section, the opposite rail of said stretch and said normally closed contact; a second electromagnet, means effective when said second electromagnet becomes energized for 20 holding said member in the position which it then occupies; an energizing circuit for said second electromagnet including said control section, the opposite rail of said stretch and one of said normally open contacts; a slow acting relay, a circuit 25 for said relay including the other normally open contact, said control section, and the opposite rail of said stretch; and means controlled by said relay for controlling the speed of a car traversing said stretch.

35 10. In combination, a stretch of railway track, a series of insulated control sections formed in one rail of said stretch, a plurality of electromagnets one associated with each of said control sections, a plurality of cams one associated with each of said electromagnets and each biased to one position, means associated with each electromagnet and effective when the associated electromagnet is energized for moving the associated cam away from said one position at a predetermined speed, a plurality of contact mechanisms 40 one associated with each cam and each including a normally closed contact which becomes opened and a normally open contact which becomes closed when the associated cam has been moved away from its said one position a predetermined distance, a series of control circuits one for each electromagnet and each including the normally closed contact of the associated contact mechanism, a different one of said insulated control sections and the opposite rail of said stretch, and an electroresponsive device controlled by said normally open contacts.

11. In combination, a stretch of railway track, a braking bar located in the trackway adjacent one of the rails of said stretch and movable into engagement with a part of a car traversing said stretch for retarding the speed of the car, a plurality of electromagnets, a plurality of cams one associated with each of said electromagnets and each biased to one position, means associated with each electromagnet and effective when the associated electromagnet is energized for moving the associated cam away from said one position at a predetermined speed, a plurality of contact mechanisms one associated with each cam and each including a normally closed contact which becomes opened and a normally open contact which becomes closed when the associated cam has been moved away from its said one position a predetermined distance, a series of insulated control 55

sections formed in one rail of said stretch; a series of control circuits one for each electromagnet and each including the normally closed contact of the associated contact mechanism, a different one of said insulated control sections and the 5 opposite rail of said stretch; and means controlled by said normally open contact for controlling the braking action of said braking bar.

12. In combination, a stretch of railway track, a braking bar located in the trackway adjacent one of the rails of said stretch and movable into engagement with a part of a car traversing said stretch for retarding the speed of the car, a plurality of electromagnets, a plurality of cams one associated with each of said electromagnets and each biased to one position, means associated with each electromagnet and effective when the associated electromagnet is energized for moving the associated cam away from said one position at a predetermined speed, a plurality of contact mechanisms one associated with each cam and each including a normally closed contact which becomes opened and a normally open contact which becomes closed when the associated cam has been moved away from its said one position a predetermined distance, a series of insulated control sections formed in one rail of said stretch; a series of control circuits one for each electromagnet and each including the normally closed contact of the associated contact mechanism, a different one of said insulated control sections and the opposite rail of said stretch; a relay, a plurality of control circuits for said relay each including a different one of said normally open contacts, the associated control section, and the 30 opposite rail of said stretch, and means controlled by said relay for controlling the braking action of said car retarder.

13. In combination, a stretch of railway track, a series of insulated control sections formed in one rail of said stretch, a braking bar located in the trackway adjacent one of the rails of said stretch and movable into engagement with a part of a car traversing said stretch for retarding the speed of the car; a series of timing units one associated with each control section and each including a cam biased to one position, a contact mechanism controlled by said cam and including a normally closed contact which becomes opened and two normally open contacts which become closed when said cam is moved a predetermined distance away from said one position, a first electromagnet, means effective when said first electromagnet is energized for moving said cam away from said one position at a predetermined speed, a second electromagnet, and means effective when said second electromagnet becomes energized for retaining said cam in the position which it then occupies; a first series of energizing circuits one for the first electromagnet of each timing unit and each including the normally closed contact of the associated contact mechanism, the associated control section and the opposite rail of said stretch; a second series of energizing circuits one for the second electromagnet of each timing unit and each including one of the normally open contacts of the associated contact mechanism, the associated control section and the opposite rail of said stretch, and means controlled by the other normally open contacts for controlling said braking bar.

14. In combination, a stretch of railway track, a series of insulated control sections formed in

determined amount, an electromagnet, means effective when said electromagnet becomes energized for moving said member away from said one position at a selected one of a plurality of predetermined speeds, an energizing circuit for said electromagnet including said control section, the opposite rail of said stretch and said normally closed contact; and means controlled by said normally open contact for controlling the speed 10 of a car traversing said stretch.

19. In combination, a stretch of railway track, an insulated control section formed in one rail of said stretch, a member biased to one position, a contact mechanism including a normally closed 15 and a normally open contact, means controlled by said member for operating said contact mechanism to open said normally closed contact and close said normally open contact when said member is moved away from said one position a 20 predetermined amount, an electromagnet, variable speed means effective when said electromagnet becomes energized for moving said member away from said one position, an energizing circuit for said electromagnet including said control section, 25 the opposite rail of said stretch and said normally closed contact; and an electroresponsive device controlled by said normally open contact.

20. In combination, a stretch of railway track, an insulated control section formed in one rail 30 of said stretch, a member biased to one position, a contact mechanism including a normally closed and two normally open contacts, means controlled by said member for operating said contact mechanism to open said normally closed contact and close said normally open contacts when said member is moved away from said one position a 35 predetermined amount, a first electromagnet, variable speed means effective when said first electromagnet becomes energized for moving said member away from said one position at a predetermined speed; an energizing circuit for said first electromagnet including said control section, the opposite rail of said stretch and said normally closed contact, a second electromagnet, means 40 effective when said second electromagnet becomes energized for holding said member in the position which it then occupies; an energizing circuit for said second electromagnet including said control section, the opposite rail of said stretch and one of said normally open contacts; a car retarder associated with said stretch, and means controlled by the other normally open contact for controlling said car retarder.

21. In combination, a stretch of railway track, 50 a member biased to one position, an electromag-

net, means effective when said electromagnet becomes energized for moving said member away from said one position at a predetermined speed, a plurality of contacts arranged to be operated by said member when said member is moved away 5 from said position a predetermined distance, an energizing circuit for said electromagnet including one of said contacts, means controlled by a car traversing said stretch for controlling said circuit, and means controlled by another one of 10 said contacts for controlling the speed of the car.

22. In combination, a stretch of railway track, a member biased to one position, an electromagnet, means effective when said electromagnet becomes energized for moving said member away 15 from said one position at a predetermined speed, a plurality of contact mechanisms arranged to be selectively operated by said member in response to movement of said member away from said one position through different distances, a plurality 20 of energizing circuits for said electromagnet each controlled by a different one of said contact mechanisms, means controlled by a car traversing said stretch for controlling said energizing circuits, and means controlled by said contact mechanisms for controlling the speed of said car. 25

23. In combination, a stretch of railway track, an insulated control section formed in one rail of said stretch, a member biased to one position, a plurality of contacts, means controlled by said 30 member for operating said contacts when said member has been moved away from said one position a predetermined distance, an electromagnet, means effective when said electromagnet becomes energized for moving said member away from said one position in opposition to its bias at a predetermined speed, an energizing circuit for said electromagnet including said control section, the opposite rail of said stretch and one of said contacts, and means controlled by another of said 35 contacts for controlling the speed of the car. 40

24. In combination, a stretch of railway track, a member which is constantly rotated, an electromagnet, a contact mechanism, means responsive to rotation of said member when said electromagnet is energized for operating said contact mechanism at the expiration of a predetermined time interval, means including said contact mechanism for at times energizing said electromagnet for a plurality of time intervals the duration of each of which depends upon the speed of a car traversing said stretch, and means controlled by said contact mechanism for controlling the speed of a car traversing said stretch. 45
